Primary Examiner — Barbara Fox*Assistant Examiner* — Mehri F Bajoul(74) *Attorney, Agent, or Firm* — Hovey Willams LLP(57) **CLAIM**

The ornamental design for a pet toy, as shown and described.

DESCRIPTION

FIG. 1 is a perspective view of a pet toy embodying my design;

FIG. 2 is a front elevational view of the pet toy of FIG. 1; FIG. 3 is a right side elevational view of the pet toy of FIG. 1;

FIG. 4 is a top plan view of the pet toy of FIG. 1; FIG. 5 is a rear elevational view of the pet toy of FIG. 1; and, FIG. 6 is a bottom plan view of the pet toy of FIG. 1. The broken lines shown in the drawings depict portions of the pet toy that form no part of the claimed design.
